UNITED STATES PATENT OFFICE.

HENRI GEORGE, OF PARIS, FRANCE.

MERCURY-LAMP.

1,398,545.

Specification of Letters Patent. Patented Nov. 29, 1921.

Application filed April 4, 1919. Serial No. 287,554.

To all whom it may concern:

Be it known that I, HENRI GEORGE, citizen of the French Republic, residing at Paris, France, have invented certain new and useful Improvements in Mercury-Lamps, of which the following is a specification.

This invention has for its object to provide an improved mercury vapor quartz lamp.

10 The accompanying drawing illustrates by way of example a constructional form of an improved lamp.

1 is the illuminating tube in which the arc is formed.

15 2 is the reservoir for the mercury cathode.

3 is the reservoir for the mercury anode.

4 is the negative terminal; and

5 is the positive terminal of the lamp.

20 On the reservoir 3 there is formed a connecting conduit 6 that carries the two vessels

7 and 8. A passage or tube 6' unites the reservoir 3 with the tube 6.

This tube 6' permits circulation of the mercury vapor through the path 1, 9, 8, 15, 3 and 1. The

25 vessel 8 is connected to the upper end of the illuminating tube by a tube 9 of at least 4 mm. internal diameter. On the inside of the vessel 8 there is formed a small straight tube 10 which is pierced with a hole 11 and

30 contains a tungsten wire 12 wound in the form of a helix. This wire is connected at its upper end to the terminal 5 and its lower end is immersed in the mercury of the lamp and is connected to a terminal ring 12' seat-

35 ed against the lower end of the tube 10 and acting to hold the wire rigid. This wire serves both as an electrode and as a starting device as hereinafter described. The tube 10 extends in the lower tubular portion 15 of

40 the vessel 8, leaving a small annular space between the two tubes. The vessel 7 has a constricted portion 13 of a diameter of about 8/10 mm. only. The level of the mercury in the lamp when at rest is indicated at 14.

45 Above the mercury, instead of a vacuum, there is an atmosphere of inert gas (such as nitrogen, argon, neon, etc., preferably neon) at a high pressure of the order of 70 mm. of mercury. When this gas has been introduced, the lamp is completely sealed up.

The operation is as follows:

The lamp having been fixed horizontally on its support, it is connected to the terminals of a continuous circuit comprising a 55 series-connected rheostat 16. For the type 115 volts, this rheostat 16 is so adjusted as

to pass twelve amperes into the circuit when the cut-out switch is closed. At the moment when the current passes into the lamp, the tungsten wire 12 which has a diameter of 60 4/10 mm., is rendered incandescent. The gas filling the vessel 8 will then expand and force the mercury both into the lower tube 15 and to the top of the illuminating tube 1. The mercury thus forced back will accumulate in the vessel 7 passing through the hole 13 which has for object to deaden the oscillations of the mercury. The mercury column forced back by the gas is soon severed at the top of the tube 1, and the arc 70 then forms immediately. To ignite the lamp it is merely necessary to close the cut-out switch and to wait for 5 to 10 seconds. The formed arc continues to lengthen and assumes as its normal position the position 75 marked by the two points A and B. At this instant for the type 115 volts, the current strength is 4 amperes and the voltage at the terminals is 85 volts. When the current is cut off, the arc is extinguished. The mercury which stood at the level A, rises again in the illuminating tube and in the tube 15 at the same time as it sinks in the vessel 7, and the general level 14 is re-established 80 after the lapse of a few seconds.

85 It is essential that the gas that serves for starting the lamp (neon gives the best results) shall be eliminated from the illuminating tube during the operation of the lamp, because its presence in the said tube 90 would greatly diminish the efficiency of the lamp. This elimination is assured by the following means:

The mercury vapor which is generated abundantly in the arc, passes through the 95 tube 9 and is condensed in the vessel 8, and falls back between tubes 10 and 15 for supplying the anode. There is therefore a continuous circulation of mercury vapor along the path 1, 9, 8, 15, 6', 3, 1, 9. The mercury 100 vapor passing through these tubes eliminates completely every trace of the gas, and assures to the arc the efficiency of a mercury arc in mercury vapor. The gas serving for starting the lamp is thus completely confined 105 in the vessel 8 during the operation of the lamp.

This circulation of the mercury assures at the same time the equilibrium of the lamp from the point of view of vaporization and 110 condensation.

It is essential that the starting and dis-

tilling tube 9 shall not have a too small diameter in order that the mercury which is condensed therein shall not choke it. In such a case there would be no longer any equilibrium between the atmosphere of the arc and that of the vessel 8, and the result would be to produce sudden movements of the mercury that might extinguish the arc.

The cathode and anode reservoirs 2 and 3 are arranged in the axis of the lamp in order not to throw any shadows during its operation.

It is to be noted that the hole 13 for deadening the oscillations is situated at a point outside of the path of the current, so that there is no risk of the flow of the current being interrupted by the lodging of a bubble of gas at that point.

During the transport of the lamp the gas is able to mix with the mercury or to displace it. Consequently it is necessary to restore the gas to its proper place before lighting the lamp which has been carried for some considerable distance. For the purpose of facilitating this operation the vessels 7 and 8 are mounted side by side on the connecting conduit 6 which establishes connection between their lower ends. The operation is further facilitated by the two fold communication 9 and 15 between the gas vessel 8 and the illuminating tube.

In connection with the foregoing it is to be understood that the lines A and B do not indicate the mercury levels which are naturally horizontal and which pass through the central point of these lines but it is apparent from the specification that said lines A and B indicate the sections of the tube between which the axis is formed during normal operation.

The lamp as described, can be started and operated with alternating current. The necessary minimum voltage for starting is in this case 500 volts. It is necessary to provide a self-induction in series.

The characteristic advantages of this lamp are:

1. An automatic ignition without rocking.
2. A higher efficiency.
3. Owing to the fact that the pressure is high even in the cold state, the placing of the lamp in operative order is instantaneous, and the lamp gives its full luminous intensity immediately on starting. Also owing to this fact, the lamp is not affected by atmospheric influences.

4. Owing to no vacuum being used, the risk of in-leaking of air and of breaking through "mercury hammer" is avoided.

5. The improved lamp can be worked with alternating current.

Having now particularly described and ascertained the nature of my said invention and in what manner the same is to be performed, I declare that what I claim is:

1. A mercury vapor quartz lamp, including an illuminating tube, a mercury cathode reservoir communicating with one end of said tube, a mercury anode reservoir communicating with the other end of said tube 70 and in circuit with said cathode reservoir, a pair of communicating vessels carried by one of said reservoirs, and one of said vessels communicating with said tube and containing an atmosphere of inert gas at a high 75 pressure of the order of atmospheric pressure, substantially as described.

2. A mercury vapor quartz lamp including an illuminating tube, a mercury cathode reservoir communicating with one end of 80 said tube, a mercury anode reservoir communicating with the other end of said tube, a pair of communicating vessels carried by the anode chamber one of which is adapted to contain a supply of inert gas while the 85 other serves to receive the mercury forced out of the illuminating tube when the lamp is in operation, another tube between the gas containing vessel and the illuminating tube, a positive terminal mounted in the gas containing vessel and serving as an igniting means for the lamp, and a negative terminal connected with the cathode chamber and in circuit with the positive terminal.

3. A mercury vapor lamp as claimed in 95 claim 2 wherein a small tube is joined with the top of the gas containing vessel and terminating short of the lower end thereof, and the lower portion of the positive terminal being in the form of a helical tungsten 100 wire accommodated in the small tube and having the extreme lower end thereof immersed in the mercury.

4. In a mercury vapor lamp having an atmosphere of inert gas under high pressure, 105 the arrangement laterally with respect to an anode reservoir of an auxiliary reservoir closed at its upper part and communicating with the anode reservoir, an axial tube integral with the upper end of said reservoir 110 and open at the lower part so as to be immersed in the mercury, the tube being provided with an opening at the upper part causing communication of the latter with the reservoir which surrounds it, a spiral tungsten wire connected to the positive pole of the circuit and arranged in said tube to assure the electrical connection with the mercury contained in the anode reservoir, and means for assuring the continuous and automatic circulation of the mercury between the anode reservoir and said auxiliary reservoir. 115

5. In a mercury vapor lamp with inert gas atmosphere under high pressure, the arrangement laterally with respect to an anode reservoir, of an auxiliary reservoir closed at its upper end and communicating with the anode reservoir, an axial tube integral with the end of said last mentioned reservoir and open at its lower part so as to be im- 120 125 130

mersed in the mercury, the tube being provided with an opening at the upper part establishing communication of said latter with the reservoir surrounding it, a spiral of tungsten wire connected to the positive pole of the circuit and arranged in said tube to assure the electrical connection with the mercury which said anode reservoir contains, a conduit establishing communication between 5 the auxiliary reservoir and the part of the tube in which the arc plays, for the purpose of creating an automatic continuous circulation of the mercury between the anode reservoir and said auxiliary reservoir, and 10 means to collect the mercury at the moment of the beginning of the priming of the tube.

6. In a mercury vapor lamp with an atmosphere of inert gas under high pressure, the arrangement, laterally with respect to an 15 anode reservoir, of an auxiliary reservoir closed at its upper part and communicating with said latter, an axial tube integral with the bottom end of said reservoir and open at its lower part so as to be immersed in the 20 mercury, the tube being provided with an opening at the upper part for establishing communication thereof with the interior of the reservoir which surrounds it, a tungsten wire spiral connected to the positive pole of the circuit and arranged in said tube to assure the electrical connection with the 25 mercury contained in the anode reservoir, a passage establishing communication of said auxiliary reservoir with the part of the tube 30 in which the arc plays, another auxiliary 35

reservoir closed at its upper part and its lower part communicating with the first named auxiliary reservoir and the anode reservoir to collect the mercury at the moment at which the arc begins, and means to 40 prevent the introduction of bubbles of gas in said mercury collecting reservoir.

7. In a mercury vapor lamp having an atmosphere of inert gas under high pressure, the arrangement laterally of an anode reservoir, of an auxiliary reservoir closed at its upper part and communicating with said latter, an axial tube integral with the bottom end of said reservoir and open at its lower end so as to be immersed in the mercury, the 45 tube being provided with an opening at the upper part of said tube to establish communication between the latter and the interior of said reservoir surrounding it, a tungsten wire spiral connected to the positive 50 pole of the circuit and arranged in said tube to assure electrical connection with the mercury contained in the anode reservoir, a passage 55 establishing communication between said auxiliary reservoir and the part of the tube in which the arc plays, another auxiliary reservoir closed at its upper part, the lower part communicating with the first auxiliary reservoir and the anode reservoir, a perforated diaphragm arranged at the entrance of said reservoir for the purpose of 60 preventing entrance of gas bubbles when the level of the mercury varies in said latter.

In testimony whereof I affix my signature.
HENRI GEORGE.
